UNITED STATES PATENT OFFICE.

FRANK J. NEWTON, OF SANDWICH, ILLINOIS, ASSIGNOR OF ONE-HALF TO ERWIN E. WALLACE, OF SANDWICH, ILLINOIS.

SHIELD FOR HEADLIGHTS.

1,344,594.

Specification of Letters Patent. Patented June 22, 1920.

Application filed January 17, 1918. Serial No. 212,162.

To all whom it may concern:

Be it known that I, FRANK J. NEWTON, a citizen of the United States, residing at Sandwich, in the county of DeKalb and State of Illinois, have invented a certain new and useful Improvement in Shields for Headlights, of which the following is a full, clear, concise, and exact description, reference being had to the accompanying drawings, forming a part of this specification.

My invention relates to shields for headlights, and has to do more particularly with shields or protecting devices for use in connection with electric lamps or bulbs in headlights such as are commonly employed on automobiles; one of the principal objects being to provide a shield which, although permitting an unobstructed projection of the intense light rays toward the ground, is of such shape and construction as to intercept these intense rays and prevent the projection of a blinding glare into an approaching driver's eyes.

In a device of this character, it is desirable to have the least interception to the rays effective for lighting up the ground, but the height of the blinding glare must be kept below the approaching driver's eyes. To this end, I provide a flat body portion, which lies in a horizontal plane over the top part of the bulb or lamp and has an inclined apron at its forward end which extends downwardly a sufficient extent to prevent the direct projection of the rays from the filament above a horizontal plane through the headlight.

A further object of my invention is to provide a shield which permits the emanation of light rays toward the top of the reflector sufficiently to give a rounded appearance to the front of the headlight when the lamp is lighted, but of such construction that these rays do not throw a blinding glare high enough to catch the eyes of an approaching driver.

A further object of my invention is to provide a device of this character which is light, simple, and neat, and which is inexpensive to manufacture and may be readily applied to existing headlights without the use of any special attachments.

For a better understanding of my invention, reference is to be had to the accompanying drawings, in which like reference

characters indicate like parts, and ~~in~~ 55 which—

Figure 1 is a vertical transverse section showing my improved shield applied to an electric headlight bulb and reflector;

Fig. 2 is a plan view of the shield applied to a bulb;

Fig. 3 is a side elevation of the preferred form of my invention;

Fig. 4 is a transverse section along the line 4—4 of Fig. 3; and

Fig. 5 is a front view of an electric headlight having my invention applied thereto.

Referring now more particularly to the preferred form of my invention as shown in Figs. 1 to 5, it comprises a flat body portion 10 substantially oval in shape, as shown in Fig. 2, and having a forwardly projecting inclined apron 11 extending downwardly to a point substantially in horizontal alignment with the center of the bulb. In order to 75 secure the shield to the lamp, I preferably provide a rear portion 16 having an opening 17 therethrough which is adapted to encircle the shank or plug of the bulb, as indicated in Figs. 1 and 2, the lower part of the 80 portion 16 having two or more spring fingers 18 adapted to engage the lower portion of the bulb, the ends of these fingers 18 being preferably provided with yielding elements 19 preferably in the form of rubber tips, 85 which are adapted to frictionally engage the bulb and hold the shield in proper position after being adjusted.

The body portion 10 and front apron 11 are adapted to intercept the rays which emanate from the top of the bulb, so that the only effective rays are thrown forwardly and toward the ground. However, unless certain rays are permitted to project toward the top of the reflector, the reflector does 95 not give a nice, rounded appearance from a distance, and therefore I provide a central opening 14 in the body portion, which permits the emanation of certain light rays toward the top of the reflector, but at the 100 forward end of this opening 14 an inclined, upwardly-extending, rearwardly-projecting portion 12 is provided, being shaped to prevent the projection of direct rays of light from the filament of the bulb upwardly and 105 beyond the edge of the reflector.

Although this opening 14 alone is effective to some extent, I have found that, to get

the best results from this opening 14, the provision of diverging elements 15 prevents the projection of those rays which would reflect from the upper portion of the reflector sidewise into an approaching driver's eyes. This divergence of these elements 15, I have found from experiment, causes a sort of closing up of the rays, and, although a certain light is produced at the upper part 10 of the reflector, it is not such a blinding glare as will be harmful. These elements 15 are preferably connected at their rear ends to a shielding portion 22, which extends forwardly from the rear edge of the opening 14, this portion 22 being also effective to prevent a harmful glare from the upper part of the reflector.

These elements 15 serve a double purpose, in that they also act as spring fingers to 20 grasp the upper part of the bulb, so that by the action of the upper and lower spring fingers, together with the rear portion of the shield, the device is firmly held in position.

25 Referring again to the apron 11, it will be noted that the side edges 21 are inclined, gradually approaching the flat part of the body portion 10 and being of such shape that they shield the filament, or intercept 30 the rays emanating therefrom and prevent the projection of these rays into an approaching driver's eyes. These inclined edges 21 extend only far enough to intercept the rays from the lamp, this shape being obtained because the angle of vision of 35 the approaching driver is gradually changing; that is, when a driver is several hundred yards from the headlight, the angle of vision is but a few degrees above the horizontal plane, so that, in order to prevent the glare from having a harmful effect, 40 the apron 11 is brought down far enough to cover the filament, but it will be apparent that as the driver approaches the headlight, the angle of vision changes and therefore it is not necessary to continue the edge 45 21 on a horizontal plane with the filament. Therefore, I gradually incline the edge 21 so that it extends just far enough to intercept the rays, but every bit of unnecessary 50 metal is eliminated. Thus, the shield is made as light as possible.

In the use of the device it is placed in position upon the bulb, as shown in Fig. 2, 55 and the bulb is then inserted into the reflector, as shown in Fig. 1, after which the shield is adjusted so that the lower edge of the apron is substantially in alignment with the filament and the lamp properly adjusted in the reflector 20. This reflector 20 is 60 preferably of the parabolic type, although my invention is not limited to any particular design of reflector. With the bulb properly adjusted in or behind the focus of the reflector and the shield properly adjusted

upon the bulb, the intense rays of the light are projected forwardly and not above a horizontal plane through the bulb, so that the blinding glare, although projected upon the road in front of the car, does not 70 extend upwardly into the approaching driver's eyes. The opening 14, however, in the top of the body portion permits sufficient emanation of light to give a nice, rounded appearance to the reflector when 75 seen from a distance; but, as already described, the presence of the diverging elements 15 prevents a sidewise projection of rays from the upper portion of the reflector, and has a peculiar effect of sort of closing 80 up the rays reflected from the upper part of the headlight as the approaching driver gradually nears the car.

In the construction of my invention I preferably employ metal, the device being 85 formed out of sheet-metal and finished with an aluminum paint. However, other material may be used if desired.

For the purpose of illustrating my invention, I have shown a single preferred form, 90 but it is to be understood that I contemplate making my invention in various sizes and to suit different types of lamps and reflectors. It is also to be understood that my invention is not limited to the precise 95 form illustrated and described, but that various changes and modifications may be made; therefore, I do not desire to be limited to the precise construction shown and described, but aim to cover all that which 100 comes within the spirit and scope of the appended claims.

What I claim as new and desire to secure by Letters Patent is:

1. A shield for head-lights comprising a 105 flat body portion horizontally positioned over the bulb, an inclined apron at the front end of the body portion adapted to extend over the front of the bulb, a central opening in the body portion over the bulb, an 110 inclined apron extending rearwardly at the forward end of the opening so as to limit the forward angle of direct emanation of rays, and means for securing the shield in position.

2. An integral sheet metal shield for headlights comprising a flat-like slightly rounded body portion adapted to be positioned over the top of the bulb and having a central opening at the top of the shield 120 so as to set down over the bulb and permit extension thereof through the shield, a forwardly extending apron for the shield so as to prevent excessive upward emanation of light rays, and a second apron rearwardly extending and forming an edge of the upper opening so as to limit the angle of direct forward emanation of light rays.

3. A shield for head-lights comprising a 125 body portion, adapted to be positioned over

- the top of the bulb and having a central opening to permit emanation of the light rays upwardly toward the reflector, a yielding holding element extending forward from the rear edge of the opening, and a second yielding holding element formed on the body portion, said holding elements engaging the top and bottom of the bulb to retain the body portion in any desired position on the bulb.
4. A shield for head-lights comprising a body portion adapted to be positioned over the top of the bulb and having a central opening to permit emanation of the light rays upwardly toward the reflector, and converging spring fingers located within the opening and joined at the rear edge thereof.
5. A shield for head-lights comprising a body portion adapted to be positioned over the top of the bulb and having a central opening to permit emanation of the light rays upwardly toward the reflector, and two spring fingers located within the opening and positioned to prevent light rays from being reflected sidewise into an approaching driver's eyes.
6. A shield for head-light bulbs comprising a flat body portion horizontally positioned above the bulb and having an inclined apron at its forward end, said body portion also having a central opening therein, fingers on said body portion engaging the underside of the bulb, and spring fingers positioned within the opening adapted to grasp the top of the bulb.
7. A shield for head-light bulbs comprising a flat body portion horizontally positioned above the bulb and having an inclined apron at its forward end extending downwardly substantially to the center of the bulb and spring fingers extending from the body portion and adapted to grasp the bulb to hold the shield.
8. The combination with a reflector and a light bulb therefor, of a shield comprising an oval body portion positioned above the bulb and having an inclined apron at its forward end extending downwardly into substantial alinement with the filament, the side edges of the apron forming a gradual incline so as to just prevent the projection of the direct rays into a driver's eyes as he approaches.

In witness whereof I hereunto subscribe my name this 31st day of December, A. D., 1917.

FRANK J. NEWTON.
